DESIGN FOR AN AUTOGRAPHIC REGISTER

Russell Katz, Hamilton, Ohio, assignor to Paul Benninghofen and Eleanor C. Diesbach, both of Hamilton, Ohio, trustees

Application September 30, 1947, Serial No. 141,668

Term of patent 14 years

(Cl. D74—5)

To all whom it may concern:

Be it known that I, Russell Katz, a citizen of the United States, residing at Hamilton, in the county of Butler and State of Ohio, have invented a new, original, and ornamental Design for an Autographic Register, of which the following is a specification, reference being had to the accompanying drawing, forming a part thereof.

I claim:

The ornamental design for an autographic register, substantially as shown.

RUSSELL KATZ.
